CLAIM

The ornamental design for a dosing closure, as shown and described.

DESCRIPTION

FIG. 1 is a rear perspective view of a dosing closure showing our new design;

FIG. 2 is a front perspective view thereof;

FIG. 3 is a side view thereof;

FIG. 4 is a side view, opposite FIG. 3, thereof;

FIG. 5 is a rear view thereof;

FIG. 6 is a top view thereof; and,

FIG. 7 is a bottom view thereof.

The broken lines are shown for the purpose of illustrating parts of the article that form no part of the claim.

1 Claim, 7 Drawing Sheets
